UNITED STATES PATENT OFFICE.

PATRICK D. SKAHEN, OF SYRACUSE, NEW YORK.

SHEET-METAL FORM FOR CONCRETE WALLS.

1,246,337.

Specification of Letters Patent. Patented Nov. 13, 1917.

Application filed April 15, 1915. Serial No. 21,491.

To all whom it may concern:

Be it known that I, PATRICK D. SKAHEN, a citizen of the United States, and a resident of Syracuse, in the county of Onondaga and 5 State of New York, have invented a certain new and useful Sheet-Metal Form for Concrete Walls, of which the following is a specification.

This invention has for its object a sheet 10 metal form for concrete walls, which is particularly simple in construction, efficient in use and which can be readily erected and knocked down; and the invention consists in the combinations and constructions hereinafter set forth and claimed.

In describing this invention, reference is had to the accompanying drawings, in which like characters designate corresponding parts in all the views.

20 Figure 1 is a plan view, partly in section, of one embodiment of this form showing various contours and shapes of concrete walls that can be formed therewith.

Fig. 2 is an elevation partly in section, 25 looking to the left in Fig. 1.

Fig. 3 is a fragmentary view showing a corner post in section and the contiguous ends of two form elements or planks, one of said elements being in section.

30 Fig. 4 is an end elevation of one of the form elements or planks.

Fig. 5 is a modified form of one of the form elements.

Fig. 6 is a modified form of another of 35 the form elements.

This form for concrete walls comprises corner posts, intermediate posts and elements or planks between the posts.

Each form usually consists of inner and 40 outer parallel walls between which the concrete or cement is poured. The corner posts consist of inner and outer pieces or strips 1, 2, the margins of the flanges of which on the sides of the angle, are spaced apart to 45 form channels 3. The post also may include a central or intermediate spacing piece 4 arranged between the pieces 1, 2, at the angle thereof and serving to space apart the pieces 1, 2, the edges of the piece 4 terminating short of the edges of the strips 1, 50 2 so that the margins of the latter form said channels 3.

The intermediate posts also include inner and outer flat pieces 5, 6 having their side 55 margins spaced apart forming channels 7. These posts may also include intermediate

spacing pieces 8 similar to the pieces 4 of the corner posts. But as seen in Fig. 5, the intermediate portion 9 of the outer piece, as 6, may be depressed and the inner piece 5 60 secured directly thereto. The outer piece 6 is here shown as bent up into the form of a channel iron, the channel 10 of which faces outwardly and the web of which is opposed to the piece 5 to form the sides of the channels 7. The intermediate posts may be stiffened by angle irons 10¹ fitted in the channel 10 between and near the ends of the posts.

All the pieces of the corner posts and the intermediate posts are secured together by 70 welding.

Each form element or plank 11 consists of a strip 12 bent up in the form of a channel and tongues 13 at the ends of the strip extending beyond the ends of the channel and 75 continuing in the direction of the web of the strip, the tongues being unprovided with the side flanges such as form the sides of the channel of the strip of the plank. Said tongues 13 are out of alinement with the web 80 of the strip 12 and are designed to enter the channels 3 of the corner posts and the channels 7 of the intermediate posts, and are located far enough out of alinement with the web of the strip to permit the outer face of 85 the web, which face engages the cement or concrete, to come flush with the adjoining faces of the corner post and of the intermediate post. Hence, the surface of the cement wall will be even when the form is removed.

As here shown, portions of the tongues fit into the channel of the strip 12 and lie against the interior face of the web or back of the strip 12, and are formed with 95 angular flanges or bases 14 which fit between the side flanges of the strip 12.

The strips 12 are stiffened so as not to bulge at their intermediate portions by braces 15 formed of angle iron. These 100 braces may be arranged as shown in Figs. 2 and 4, as extending lengthwise of the planks, or as shown in Fig. 6, as extending obliquely crosswise thereof within the channel.

105 In use, it will be understood that the planks are arranged one above the other.

This form may also include planks designed to be arranged in vertical position and having lengthwise flanges designed to 110 fit into the channels 3 of the corner posts. These vertical planks are particularly use-

ful in connection with the corner posts, to form pilasters.

16 designates the vertical planks, each of which includes a body plate 17 and angle 5 plates 18 mounted on the margins of the plate 17 and having flanges 19 extending beyond the side edges of the plate 17 in order to enter the channels 3 of the corner posts.

This form can be adjusted to various 10 thicknesses and contours of walls, and the form walls, when spaced the desired distance apart, are held by suitable tie pieces 20 connected to the intermediate posts and planks.

15 The planks 11 are held in position by tie pieces 21 connected to the ends of the planks on one side of a corner post and extending past said post and connected to the ends of the planks on the other side of the 20 post. These tie pieces are usually wire cables.

What I claim is:—

1. A sheet metal plank for concrete forms comprising a strip bent in the form of a channel and a tongue projecting beyond the 25 end of said channel and being secured directly to the web at the bottom of the channel and extending from the web at the bottom of the channel in the direction of said web, substantially as and for the purpose 30 set forth.

2. A sheet metal plank for concrete forms comprising a strip bent in the form of a channel and a tongue set in the channel and projecting beyond the end of the channel in 35 the direction of the web of the channel, substantially as and for the purpose set forth.

3. A sheet metal plank for concrete forms comprising a strip bent in the form of a channel, and a tongue set in the channel and

projecting beyond the end of the channel in 40 the direction of the web of the channel, the tongue lying against the inner face of the web, substantially as and for the purpose described.

4. A sheet metal plank for concrete forms 45 comprising a strip bent in the form of a channel, and a tongue set in the channel and projecting beyond the end of the channel in the direction of the web of the channel, the tongue lying against the inner face of the 50 web, and having an angular flange fitting between the side flanges of the channel, substantially as and for the purpose specified.

5. A sheet metal concrete form element comprising an elongated strip bent in the 55 form of a channel and angle iron bracing strips located in the channel and secured to the web of the channel, substantially as and for the purpose specified.

6. A sheet metal concrete form element 60 comprising a flat body strip and angle strips mounted on the margins of the body strip and arranged with flanges thereof projecting beyond the edges of the margins of said body strip forming tongues, one of the sides 65 of the angle strip lying flat against the web of the body strip, substantially as and for the purpose set forth.

In testimony whereof, I have hereunto signed my name in the presence of two attesting witnesses, at Syracuse, in the county of Onondaga, and State of New York, this 70 3rd day of November, 1914.

PATRICK D. SKAHEN.
